COMPARTMENTED CONTAINER

Noel A. Petter, Los Angeles, Calif., assignor to
 Standard Paper Box Corp., Los Angeles, Calif.,
 a corporation of Delaware

Application August 1, 1949, Serial No. 4,235

Term of patent 14 years

(Cl. D58—13)

To all whom it may concern:

Be it known that I, Noel A. Petter, a citizen of the United States of America, residing at Los Angeles, in the county of Los Angeles and State of California, have invented a new, original and ornamental Design for a Compartmented Container, of which the following is a specification, reference being had to the accompanying drawings, forming a part thereof.

In the drawings:

Figure 1 is a perspective view of a compartmented container, showing my new design; and

Figure 2 is a perspective view, partly broken away for convenience of illustration, showing the side and end opposite those shown in Figure 1.

I claim:

The ornamental design for a compartmented container, as shown.

NOEL A. PETTER.
